UNITED STATES PATENT OFFICE.

LEON S. GREENBERG, OF NEWARK, NEW JERSEY.

MOLDING-FLASK.

1,331,193.

Specification of Letters Patent. Patented Feb. 17, 1920.

Application filed August 9, 1919. Serial No. 316,427.

To all whom it may concern:

Be it known that I, LEON S. GREENBERG, of the city of Newark, county of Essex, and State of New Jersey, have invented certain 5 new and useful Improvements in Molding-Flasks, of which the following is a full, clear, and exact description.

My invention relates to improvements in molding flasks, which, although capable of 10 general use for molding plastic substances and casting metals, is more especially designed for the use of dentists in the molding of dental plates.

One object of my invention is to provide 15 a molding flask which will permit the necessary amount of pressure to be brought upon the double headed locking pins, which lock the middle portion to the top and bottom portions of the device, while manufacturing 20 dentures, without liability of said plates giving way by bending or breaking.

Another object of my invention is to provide a molding flask which dispenses with the use of nuts and bolts as separate parts.

25 Another object of my invention is to provide a molding flask, the top of which can be readily removed and the remainder still be locked leaving the invested teeth in the receptacle in appropriate position for working thereon.

Another object of my invention is to provide a molding flask of greater simplicity and adjustability, easier to disengage and of less parts than similar flasks now in use.

35 With the above and other uses in view, the invention consists in the novel construction, combination, and arrangement of parts hereinafter described, and claimed, and illustrated in the accompanying drawing 40 forming a part of the specification, in which;

Figure 1 is a perspective view of the flask showing the several parts thereof disconnected.

45 Fig. 2 is a plan view of the assembled flask, the top plate being partially broken away to show the middle piece.

Fig. 3 is a cross section view of the device on line 2—2, of Fig. 2 showing means for 50 holding the members of the flask together.

The molding flask as illustrated in Fig. 1 is composed of a bottom piece or receptacle 1, middle piece 2, and a top piece or plate 3.

Bottom piece 1, Fig. 1, is provided with recesses or apertures formed within projections or extended portions 5^a, 5^b, and 5^c of

the general shape shown, adapted to fit over shoulders 8^a, 8^b, and 8^c respectively, which are provided on under portion of middle piece 2 and integral therewith. Projections 5^a, 5^b, and 5^c are constructed so as to permit the heads of locking pins 9^a, 9^b, and 9^c to turn while the device is resting on a flat surface, more clearly shown in Figs. 1 and 3, as 60 14^a, 14^b, and 14^c. A middle piece 2, Fig. 1, 65 is detachably fastened or locked to bottom piece 1 and to top plate 3 by means of a multiple of double headed locking pins 11^a, 11^b, and 11^c, more clearly shown in Fig. 3. Middle piece 2 is provided with projections 70 10^a, 10^b, and 10^c, and on the upper portion thereof respectively are provided three elongated shoulders 7^a, 7^b, and 7^c of a shape to correspond and fit the recesses provided on top plate 3 within projections or prongs 4^a, 75 4^b, and 4^c respectively. Middle piece 2, Fig. 1, is also provided, integral therewith, with the herein before mentioned three shoulders 8^a, 8^b, and 8^c on the under portion of projections 10^a, 10^b, and 10^c respectively, of 80 similar elongated shape but slightly longer than shoulders 7^a, 7^b, and 7^c in order to correspond with the thickness of bottom piece 1 and made to fit recesses provided within projections 5^a, 5^b, and 5^c, on bottom piece 1. 85 A hole is provided through each projection 10^a, 10^b, and 10^c and the corresponding shoulders on both upper and under sides thereof, through which locking pins 11^a, 11^b, and 11^c respectively are inserted. These 90 locking pins are each provided on the upper ends thereof with elongated heads 6^a, 6^b, and 6^c respectively, and on the lower ends with similar heads 9^a, 9^b, and 9^c, Figs. 1 and 3. These heads are firmly riveted, pinned, or 95 otherwise immovably attached to the locking pins, making what are called double headed locking pins, all of the same general shape, and made to fit their respective recesses snugly, so that when they are turned with the fingers the device is securely and firmly locked. The turning of one head reciprocally turns the opposite head, and thus 100 the device may be locked or unlocked as desired. Middle piece 2 is further provided with a peculiar downward projecting portion 12 integral therewith fitting in a depressed portion 13 integral with bottom piece 1, as illustrated in Fig. 1, by means of which these two pieces are more firmly held 105 in place and also providing a properly formed mold for dental work. Top plate 3,

Fig. 1, is of the same general shape as the other two principal pieces. It is provided with projections or prongs 4^a, 4^b, and 4^c forming recesses to correspond and fit over 5 shoulders 7^a, 7^b, and 7^c respectively of middle piece 2, Figs. 1 and 2. Top piece or plate 3 is flat in respect to its upper and lower sides differing in this respect from the other principal pieces. A slight alternate 10 modification is now noted by providing instead of the flat surface of top piece 3 a slight gradual increase in thickness of the extended portions or prongs 4^a, 4^b, and 4^c directly under where the upper heads 6^a, 6^b, 15 and 6^c turn, so that when the device is locked such thickness of the prongs will take up any ordinary wear which may be caused by the frequent turning of the double headed locking pins.

20 In use my improved molding flask, after preparing the mold, is assembled by locking the bottom piece 1 to middle piece 2, into which the mold is then placed, after which top plate 3 is placed on middle piece 2, and 25 the three pieces are locked by simply turning with the fingers each of the double headed locking pins 11^a, 11^b, and 11^c, by using the upper heads 6^a, 6^b, and 6^c thereof. A turn of any pin head causes a corresponding 30 motion or turn of the opposite head. For use in casting metals it would be necessary to provide a passage or opening in top plate 3 of any usual shape through which the molten metal would be poured. The 35 joints between the several pieces will readily provide for the escape of any gas that may form in the mold when making such casting. To unlock the device, again turn each pin head parallel to the recesses, and top 40 plate 3 may then be removed exposing the casting, and another turn of each double headed locking pin locks the middle piece 2 and bottom piece 1 again, which cannot be accomplished with other known flasks, and 45 work may be performed on the casting in that position, or it may be entirely removed. Various changes within the scope of the 50 invention defined in the following claims may be made in the particular construction of the device and also in the size and organization of the pieces thereof without departing from the spirit of my invention, such as the addition of another ring to make a higher molding flask which is sometimes 55 desirable.

I am aware that prior to my invention vulcanizing or molding flasks have been made comprising top, bottom and middle pieces of the same general shape, and for 60 the same use as mine, but not with the peculiar shape and special features thereof, or with the novel means for locking provided in my invention, I therefore do not claim the combination of the principal members broadly, but what I do claim as my 65

invention and desire to secure by Letters-Patent, is—

1. In a molding flask of the character described, the combination of a bottom piece, a middle piece, a top piece, and a plurality of locking pin means constructed so that either end of any pin when moved reciprocally turns the other end, for holding said pieces together, as and for the purpose described. 75

2. In a molding flask of the character described, the combination of a plurality of receptacle pieces, and a plurality of double headed locking pins constructed so that either end of any pin when moved reciprocally turns the other end, for locking and 80 unlocking said pieces, substantially as described.

3. A molding flask comprising a bottom piece, a top plate, a middle piece provided with a plurality of extended portions containing a hole through each, a plurality of locking pins one each passing through respective holes for locking top and bottom pieces to said middle piece, substantially 85 as described.

4. A molding flask comprising a middle piece provided with a plurality of extended portions, a plurality of shoulders one each projecting from upper and lower sides of said extended portions containing a hole through each of said shoulders and extended portions, a plurality of double headed locking pins means passing respectively through said holes, a bottom piece containing a multiple of recesses corresponding in shape to that of the shoulders, and a top plate containing a multiple of recesses corresponding in shape to that of the shoulders, the said bottom piece and top plate being locked to 100 the middle piece by said double headed locking pin means, substantially as described. 105

5. A molding flask comprising a bottom piece provided with a plurality of recesses in extended portions thereof and also provided with a depressed portion, a middle piece provided with a projection corresponding to and fitting in said depressed portion of bottom piece, and also provided with a plurality of extended portions with a plurality of shoulders one each projecting from the upper and lower sides of said extended portions, a plurality of double headed locking pin means, one each passing through respective holes which holes are provided through each of said shoulders and extended portions, a top plate provided with a plurality of recesses one each in extended portions thereof corresponding to shape of shoulders, substantially as and for the purpose described. 110 115

6. A molding flask comprising a bottom piece provided with a plurality of projections each containing a recess therein, said projections being raised from the underside 120 125 130

of bottom piece a sufficient distance to allow the heads of locking pins to freely turn when the device is assembled, and also provided with a depressed portion, a middle piece provided with a projection corresponding to and fitting in said depressed portion of bottom piece, and also provided with a plurality of extended portions and with a plurality of shoulders one each projecting from the upper and lower sides of said extended portions, with a hole through each of said shoulders and extended portions, a top plate provided with a plurality of extended portions and with a plurality of recesses one in each pair of extended portions thereof corresponding to shape of shoulders, and a plurality of double headed locking pins one each passing through said holes to lock the top plate and bottom piece to the middle piece substantially as and for the purpose described.

7. A molding flask comprising a bottom piece provided with a plurality of projections each containing a recess therein said projections being raised from the under side of bottom piece a sufficient distance to al-

low the heads of locking pins to freely turn when the device is assembled, and also provided with a depressed portion, a middle piece provided with a projection corresponding to and fitting in said depressed portion of bottom piece, said middle piece being also provided with a plurality of extended portions, and with a plurality of shoulders one each projecting from the upper and lower sides of said extended portions, a top plate provided with a plurality of recesses one each in extended portions thereof corresponding to shape of shoulders, and also provided with a plurality of slightly thickened portions on top of each prong of extended portions, and a plurality of double headed locking pins to lock bottom piece and top plate to middle piece, substantially as and for the purpose described.

In testimony whereof I affix my signature in the presence of two witnesses.
